UNITED STATES PATENT OFFICE

147,388

DESIGN FOR A COMBINED RANGE TOP AND
BACK GUARD ASSEMBLY

Ralph E. Kruck, Longmeadow, Mass., assignor to
Florence Stove Company, Gardner, Mass., a
corporation of Massachusetts

Application February 13, 1946, Serial No. 126,544

Term of patent 14 years

(Cl. D81—25)

To all whom it may concern:

Be it known that Ralph E. Kruck, a citizen of the United States, residing at Longmeadow, in the county of Hampden and Commonwealth of Massachusetts, has invented a new, original, and ornamental Design for a Combined Range Top and Back Guard Assembly, of which the following is a specification, reference being had to the accompanying drawing, forming part thereof.

Fig. 1 is a perspective view of a combined range top and back guard assembly, showing my new design; and

Fig. 2 is a fragmentary elevational view on an enlarged scale taken from the right of Fig. 1, with portions of the back guard and the range top omitted for convenience of illustration.

The dominant features of the design reside in the portions shown in full lines.

I claim:

The ornamental design for a combined range top and back guard assembly, as shown and described.

RALPH E. KRUCK.
